ANTENNA TENSIONING DEVICE

Herbert Brühe, Berlin, Germany, assignor to
 Siemens & Halske Aktiengesellschaft, Siemens-
 stadt, near Berlin, Germany, a corporation of
 Germany

Application February 24, 1936, Serial No. 65,533
 In Germany March 22, 1935

2 Claims. (Cl. 267—71)

In antenna arrangements on vehicles such as trains for train telephony, for example, it is of importance to provide antenna wires which only sag a small amount. Consequently, they must 5 always be maintained straight. The antenna conductors are, however, subjected to vibrations and high wind pressure so that in order to avoid breakage a yielding tensioning means should be provided. To this end spring arrangements or weights are inserted between the antenna support and the conductor. Such spring tensioners are subject to especially rapid destruction since they are continuously exposed to 10 atmospheric conditions, especially frost and ice, and to chemically active constituents contained 15 in the smoke of the locomotive especially effective in connection with humidity. These influences mainly cause deterioration of the material and finally lead to complete destruction.

20 My invention relates to an arrangement for tensioning antennas, and which is protected effectively against destructive influences. According to the invention a helical spring producing the tensioning of the antenna is arranged within 25 a weather proof, cup-shaped casing resting at one side against the cover of the casing and connected at the other side to a member attached to the antenna and inserted through the inner space of the spring and through the cover of the 30 casing. Said member may constitute a cylindrical bolt, for example. The casing preferably consists of a material having high resistance against corrosion or it is coated with a paint, thereby resisting the destructive actions caused by the 35 aforementioned influences for a long period of time. In order to prevent humidity or the like entering the interior of the tensioning device the casing is suitably filled-in with a grease resistible to acid and low temperatures, and serving at the 40 same time as packing material for the passage of the bolt attached to the antenna. At this place of through passage the bolt is inserted with a certain play so as to obtain at this place always a sufficient lubrication.

45 The entrance of humidity and moisture between casing and cover is prevented by the provision of an interposed packing ring. At the cover the tensioning device rests against a support maintaining the antenna at a certain distance from the roof of the car and fastened to the casing by means of the screws used for fastening the cover in place.

For a better understanding of the invention reference is made to the accompanying drawing 55 in which the drawing shows a single embodiment

thereof in partial section along the axis of the device.

Numerical 1 represents the cup-shaped casing of the new tensioning device, closed at its open end by means of a cover 2 placed by means of an interposed packing 3 of leather, rubber or the like upon the flange-shaped rim 4 of the casing.

For fastening the cover, four screws 5 are employed equally distributed about its circumference and serving at the same time for fastening the 10 tensioning device to an angle-shaped support 6 which may be mounted on the roof 20 of the vehicle. In the casing 1 there is arranged a helical spring 7 shown in a greatly de-tensioned state resting at its right end against the inner side of 15 the housing cover 2 and attached at the left end to a plate-shaped flange 8 provided at the end of a bolt 9. This bolt is inserted through the cover and the guide bushing 10 fastened to the cover 2 and is attached to the antenna. It can readily 20 be seen that in case of longitudinal variations of the antenna, such as shortening for instance, due to temperature influences or high wind pressure, the spring 7 will be compressed and the flange-shaped disk 8, together with bolt 9, is moved to 25 the right.

For fastening the antenna to the end of bolt 9 projecting from the guide bushing 10, a link 11 is provided passed through a lateral bore 15 of the bolt. To provide a continuous tension in the antenna it is necessary that the device be mounted under a certain initial tension i. e. the spring 7 30 is in a tensioned state whereby the flange 8 is withdrawn from the bottom 12 of the housing and the spring is compressed to about one-half of 35 the length thereof shown in the figure by means of the flange 8 and the bolt 9. In this manner movement of the bolt in any direction of its axis is assured so that it can adjust itself to any length 40 of the antenna.

The guide bushing 10 is inserted through the bore 13 of the support 6. For the purpose of fastening the support 6, bores 14 are preferably provided in the part resting on the roof 20 of the car which serve to receive fastening screws or 45 bolts 714' and the like.

As already pointed out, the interior of the housing is preferably filled in with a grease which is free of acid and proof against cold while continuously effecting a sufficient sealing of the bolt 50 9 passing through the bushing 10 with sufficient play thereby preventing the entering of detrimental particles into the tensioning device and finally assuring a sufficient lubrication of the bearing.

Having described my invention, what I claim as novel and desire to secure by Letters Patent is:

1. Means for yieldingly supporting an antenna comprising in combination, a tubular casing closed at one end and open at the other, a member for rigidly supporting said casing, a cover plate having an aperture therein, securing means for attaching said cover plate to the open end of said casing, a rod passing through said aperture, a coil spring within the casing having one end connected to the inner end of said rod and the other end abutting the cover plate, a body of lubricant within said casing around said rod and spring, and means for connecting the outer end 10 of said rod to the antenna.

2. Means for tensioning and yieldably supporting one end of an antenna, said means comprising a rigidly supported tubular casing closed at one end, a rod member within the casing and extending partly through the open end of the 5 casing, a cover plate secured at the open end of the casing having an opening through which the rod member extends, a helical spring contained within the casing and encircling the rod member, one end of the spring being fastened to the inner 10 end of the rod and the other end of the spring abutting the cover plate, and means at the free end of the rod member to which the antenna is adapted to be attached.

HERBERT BRÜHE. 15
